UNITED STATES PATENT OFFICE.

CHARLES P. KNAPP, OF DEPOSIT, NEW YORK.

DESIGN FOR A STRETCHER-PLATE FOR CARPET-TACKING DEVICES.

SPECIFICATION forming part of Design No. 32,343, dated March 13, 1900.

Application filed February 12, 1900. Serial No. 5,022. Term of patent 7 years.

to all whom it may concern:

Be it known that I, CHARLES P. KNAPP, a citizen of the United States, residing at Deposit, in the county of Delaware and State of New York, have invented and produced a new original Design for a Stretcher-Plate for Carpet-Tacking Devices, of which the following is a full, clear, and exact description.

Reference is to be had to the accompanying drawings, in which—

Figure 1 is a plan view of a stretcher-plate embodying the features of my design. Fig. 2 is a section thereof on the line 2 2 of Fig. 1. Fig. 3 is an edge view, and Fig. 4 is an inverted plan.

The essential features of my design consist in the design made the subject of the accompanying drawings, in which the plate is shown as approximately triangular in shape, within the three sides A, B, and C of which appears a rectangular block D, from whose corners

emanate arms E, extending to the sides A and B, and arms F, extending to the side C, thereby causing four openings A', B', C', and D' to appear. The sides A and B are formed with 25 prongs G and G', arranged in horizontally-aligned pairs, the prongs G being curved in one direction, while the prongs G' are straight, and prongs G² appear on the side C, said latter prongs being curved in an opposite direction from the prongs G and terminating in a higher plane than the said prongs G. 30

I claim—

The design for a stretcher-plate for carpet-tacking devices, herein shown and described. 35

In testimony whereof I have signed my name to this specification in the presence of two subscribing witnesses.

CHAS. P. KNAPP.
